SPEED RESPONSIVE DEVICE

John H. Stresen-Reuter, Birmingham, and John F. Vis-mara, Detroit, Mich., assignors to Holley Carburetor Company, Warren, Mich., a corporation of Michigan
Filed June 5, 1964, Ser. No. 372,910
3 Claims. (Cl. 200—80)

This invention relates generally to electrical switches, and more particularly to a switch having means for actuating an electrical switch in response to some sensed speed.

There are many applications wherein it is desirable to operate a switch as a function of the speed of an associated engine. For example, in conjunction with the development of automotive gas turbine engines, it has been found desirable to provide means for actuating a switch so as to cut off the igniter system upon attainment of a predetermined engine speed.

Accordingly, a general object of the invention is to provide a switch having means responsive to sensed engine speed for opening the switch when the engine reaches a predetermined speed.

Another object of the invention is to provide such means which transforms a rotary motion indicative of engine speed into a corresponding linear motion.

Still another object of the invention is to provide such a means which is compact in design and efficient in operation.

A more specific object of the invention is to provide such a means comprising a sleeve slidably and rotatably mounted on a rotating shaft, a novel centrifugal means for moving the sleeve axially along the shaft while both are rotating, and an associated L-shaped lever, one leg of which is actuated about a pivot at the juncture between its legs in response to the axial movement of the rotating sleeve, the free leg being associated with a switch for opening and closing the same.

A further object of the invention is to provide such a means which includes a "through drive" feature, enabling it to additionally operate a speedometer or a tachometer cable.

A still further object of the invention is to provide such a means which includes mechanism for limiting the force applied to the switch during overspeed conditions.

Other objects and advantages of the invention will become more apparent when reference is made to the following specification and the accompanying drawings wherein:

FIGURE 1 is a side elevational view of a switch embodying the invention;

FIGURE 2 is an end view, in fragmentary cross-section, taken along the plane of line 2—2 of FIGURE 1 and looking in the direction of the arrows;

FIGURE 3 is a fragmentary cross-sectional view taken along the plane of line 3—3 of FIGURE 1 and looking in the direction of the arrows;

FIGURE 4 is a fragmentary cross-sectional view taken along the plane of line 4—4 of FIGURE 1 and looking in the direction of the arrows; and

FIGURE 5 is a fragmentary cross-sectional view of a modification of the invention.

Referring now to the drawings in greater detail, FIGURE 1 illustrates a speed responsive switch assembly 10, including a lightweight housing 12 having a chamber 14 formed therein and closed at one end by a cover plate 16, the latter being fastened to the housing 12 by any suitable means such as bolts 18. The opposing end 19 of the housing 12, as well as the hub 20 of the cover plate 16, are externally threaded and have openings 21 and 22

2

formed therein. Bearings 24 and 26 may be inserted in the openings 21 and 22, respectively.

A shaft 28, which extends through the chamber 14, is fitted at its ends into the bearings 24 and 26. A collar 30 may be formed on or secured to the shaft 28 in order to control the depth to which the shaft 28 is inserted into the bearing 24 in the housing 12. A connecting means, such as non-circular holes 32 (FIGURES 1 and 2), may be formed in both ends of the shaft 28 suitable for receiving a driving means, such as a flexible cable 33. A flanged sleeve 34 is slidably mounted around the shaft 28 such that the flanged end 36 is adjacent the collar 30, and a suitable bearing 38 is secured to the sleeve 34 adjacent the flange 36. A recessed washer 40 is loosely mounted around the sleeve 34 and positioned with its outer edge 42 against the bearing 38.

A rectangular or other suitably shaped block 44 is secured to the sleeve 34 at a predetermined distance from the flange 36, and a second block 46 is fixedly secured to the shaft 28 at a point adjacent the cover plate 16. The block 46 may be secured to the shaft 28 by any suitable means such as by a pin 47 aligned in holes formed through the block 46 and the shaft 28. A suitable resilient means, such as a spring 48, is confined between the block 46 and spring retainer 49 adjacent the bearing 26 and serves to hold the bearing 26 in the cover plate 16.

Two pair of U-shaped round wire links 50 and 52, each link having one long and one short leg identified as 54 and 56, respectively, (FIGURE 3) serve to connect the two rectangular blocks 44 and 46 and to thereby cause the sleeve 34 to rotate with the shaft 28. Due to the pivotal connections described below, the links 50 and 52 also permit the sleeve 34 to move axially along the shaft 28 a distance which has a linear relationship to the speed at which the shaft 28 is rotating. The longer legs 54 are pivotally retained within openings 58 formed through the two rectangular blocks 44 and 46 by means of cotter pins 60 (FIGURE 1) inserted through transverse openings 62 (FIGURE 3) formed through the exposed ends of the longer legs 54.

As illustrated in FIGURE 3, the longer legs 54 are inserted through the openings 58 in the rectangular blocks 44 and 46 in opposite directions, thereby causing the short legs 56 of opposing links 50 or 52 to be pointed toward one another. Each of the pair of flyweight balls 64 has a diametrical hole 66 formed therethrough to receive the short legs 56 of the opposing U-shaped links 50 or 52. However, the short legs 56 are first inserted through the round and elongated openings 68 and 70, respectively, formed near the ends of each thin metal strap 72, as illustrated in FIGURE 1. That is there is a strap 72 on each side of the balls 64 and each strap 72 has a round opening 68 and a slot 70, the straps 72 serving to limit the outward movement of the balls 64.

A generally L-shaped lever 74 having a forked end 76 (FIGURE 4) formed in its leg 78 suitable for straddling the sleeve 34 between the rectangular block 44 and the washer 40, is pivotally mounted at the juncture 80 between its legs 78 and 82 in the chamber 14 by means of a pivot pin 84 secured to the housing 12. A suitable resilient means, such as a spring 86, is mounted between a spring seat 88 and a projection 90 formed on the leg 82 of the L-shaped lever 74. An adjusting screw 92 mounted in a threaded opening in the wall of the housing 12 and abutted at its internal end 94 against the spring seat 88, serves to permit manual adjustment of the spring 86.

A standard electrical switch 96 having a pair of leads 98 and 100 (FIGURE 2) extending therefrom is adjust-

ably mounted within the chamber 14 by means of a metal bracket 102, the latter being fastened down by screws 103. The bracket 102 contains an elongated opening 104 near one of its ends suitable for permitting manual adjustment of the switch 96 toward or away from the bent end 106 of the L-shaped lever 74 for proper alignment therewith. The detailed internal structure of the switch 96 is not material to the invention, the particular switch shown being normally closed by a spring and being opened by upward movement of the actuator 107 by the end 106 of the lever 74.

Operation

In a typical application, the shaft 28 is rotated by the flexible cable 33, which may be connected between the square opening 32 of either end of the shaft 28 and a gear reduction system (not shown), in some direct proportion to the speed of a gas turbine engine (not shown). The threaded ends 19 and 20 facilitate mounting the speed responsive switch 10 on any suitable support structure. As the speed of the shaft 28 and the associated sleeve 34 increases, the resultant centrifugal force moves the balls 64 outwardly, the short legs 56 of the U-shaped links 50 and 52 being free to pivot in opposite directions within the opening 66 formed through the balls 64.

As the balls 64 move outwardly, the distance between the opposing longer legs 54 of the U-shaped links 50 and 52 is decreased, and the rectangular block 44 secured to the sleeve 34 is pulled toward the block 46 secured to the shaft 28. This, of course, moves the sleeve 34 axially along the shaft 28. The bearing 38 and the washer 40, as well as the forked end 76 of the leg 78 of the L-shaped lever 74, will likewise be moved axially along the shaft by the flange 36 formed on the sleeve 34. The co-operation of the bearing 38, the collar 36, the recessed washer 40 and the forked end 76 of the lever 74, permits the collar 36, sleeve 34 and inner race of the bearing 38 to rotate at the same time that the outer race of the bearing 38, the washer 40 and the forked end 76 of the lever 74 are moved axially to the right in FIGURE 1, the lever 74 pivoting counterclockwise about the pivot pin 84 against the force of the spring 86. The other end 106 of the L-shaped lever 74 is thus moved upwardly in FIGURE 1 against the normally closed switch 96, thereby breaking the circuit which actuates, for example, the igniter plugs (not shown) of the turbine engine. This, of course, would render the igniter system of the engine inoperative.

FIGURE 5 modification

When desirable, the cover plate 16, the bearing 26, the spring 48 and the flexible cable 33 may be eliminated, and the shaft 28 may be connected directly to some driving unit, such as the unit partially illustrated in FIGURE 5 and identified as 108. In this instance, the square hole 32 in the end of the shaft 28 (FIGURE 2) would be replaced by a slot 110 receiving a pin 112 having the ends thereof fixed in the shaft 113 having an opening 114 to receive the shaft 28. A spring 116 may be located in the opening 114 to keep the shaft 113 from creeping to the left along the shaft 28 and also to aid the spring 86 of the FIGURE 1 embodiment in holding the collar 30 against the bearing 24 through the L-shaped lever 74.

As modified, the housing 12 may have a flange 118 formed thereon including holes 120 for mounting purposes.

Summary

It should be apparent from the above discussion that the invention provides novel means for actuating an electrical switch in response to speed. Since the lever structure provides mechanical amplification of the speed sense, as compared to the usual centrifugal flyweight arrangement, the device may be more compactly packaged. It is further evident that a driving unit, such as the flexible cable illustrated in FIGURE 1, may be connected to

either end of the shaft at random, with the same efficient result. The "through drive" feature obviously enables the other end of the shaft to be put to use driving an accessory item, such as a speedometer or a tachometer.

Once the switch is opened by the L-shaped lever at the predetermined speed, additional movement by the lever is not necessary and, in fact, may be harmful to the switch at excessively high shaft speeds. Hence, it is evident that the straps associated with the balls and U-shaped links serve to limit the force which the L-shaped lever may exert on the switch, while not in the least interfering with the rotation of the shaft and sleeve.

The length of the slots 70 and 104, the force of the springs 48 and 84, the weight of the balls 64 and the dimensions of the lever 74 are some of the design factors that may be varied to change the operating characteristics of the switch 10.

Although but two embodiments of the invention have been disclosed and described, it is apparent that other modifications are possible within the scope of the appended claims, including uses other than a switch.

What we claim as our invention is:

1. A speed responsive switch device, comprising a rotatable shaft, a sleeve slidably and rotatably mounted around said shaft, a first member fixedly attached to said shaft, a second member fixedly attached to said sleeve, a pair of U-shaped links pivotally connected along one leg thereof to each of said first and second members, a weight having an opening therethrough for receiving the other leg of each opposing pair of links, pivotable means operatively connected to said sleeve for axial movement therewith, and a rigid member operatively connected to said links for positively limiting the outward movement of said weights, said member being pivotally connected at one end thereof to one link of one of said pairs of links and having a slot formed near the other end thereof, said slot receiving one link of said other pair of links.

2. A speed responsive switch device, comprising a shaft, means for rotating said shaft, a first member fixedly attached to said shaft, a sleeve slidably mounted around a portion of said shaft, a flange formed on one end of said sleeve, a second member fixedly attached to said sleeve, a bearing surrounding said sleeve and positioned between said second member and said flange, a pair of U-shaped links pivotally connected along one leg thereof to each of said first and second members, a weight having an opening therethrough for receiving the other leg of each opposing pair of links such that the other end of said sleeve is located a predetermined distance away from said first member while said shaft is not being rotated and with said predetermined distance diminishing with increased centrifugal force on said weight and said links, a strap pivotally connected at one end thereof to one of said links and having a slot formed in the other end thereof receiving and permitting limited movement therein of an opposing link, a pivotable L-shaped lever having one forked end straddling said sleeve between said bearing and said first member, and a switch associated with the other end of said L-shaped lever.

3. A speed responsive actuating assembly, comprising a housing forming a closed chamber, a shaft extending through said chamber and mounted for rotation therein, a sleeve mounted on said shaft so as to be movable rotationally and axially with respect to said shaft, a first cross member mounted for rotation with said shaft, a second cross member mounted for movement with said sleeve, a pair of governor weights positioned midway between said first and second cross members on opposite sides of said shaft, linkage means pivotally connected between each of said governor weights and said cross members in a manner such that increasing speed of rotation of said shaft causes said weights to move outwardly and thereby move said sleeve axially along said shaft toward said first cross member, means for positively limiting the outward movement of said weights, said means including a rigid member having one end thereof pivotally connected to

70

one of said linkage means and including a slotted opening in the other end for receiving the other of said linkage means, an abutment formed on said sleeve, a member to be actuated mounted within said housing, an L-shaped lever pivotally mounted at the juncture of its legs to said housing, one leg of said lever engaging said abutment on said sleeve and the other leg of said lever being positioned to operate said member to be actuated upon attainment of a predetermined speed of said shaft, and adjustable spring means for urging said L-shaped lever away from said member to be actuated.
